UNITED STATES PATENT OFFICE.

PETER H. LUITINK, OF MILWAUKEE, WISCONSIN, ASSIGNOR TO LUITINK AND SONS MANUFACTURING COMPANY, OF MILWAUKEE, WISCONSIN.

DOOR-HANGER.

SPECIFICATION forming part of Letters Patent No. 707,131, dated August 19, 1902.

Application filed April 18, 1902. Serial No. 103,499. (No model.)

To all whom it may concern:

Be it known that I, PETER H. LUITINK, a citizen of the United States, and a resident of Milwaukee, in the county of Milwaukee and 5 State of Wisconsin, have invented certain new and useful Improvements in Door-Hangers; and I do hereby declare that the following is a full, clear, and exact description thereof.

The improvements consist in certain peculiarities of construction and combination of parts hereinafter particularly set forth with reference to the accompanying drawings and subsequently claimed, the object of the invention being to provide simple, economical, 15 light, strong, durable, and vertically-extensible separable hangers for sliding doors, such as are used to close entrances of barns and other structures.

Figure 1 of the drawings represents a front 20 elevation of one of my improved door-hangers, partly broken and in section; Fig. 2, a central vertical section of the hanger in connection with a fragment of a door that is also in section.

25 Referring by letter to the drawings, A indicates a fragment of a door, and B a section of my improved vertically-extensible separable hanger attachable to the door. This section of the hanger is shown as being a flat

30 sheet-metal plate in one piece, with apertured corner-ears *b* and a pair of vertical outer flanges *c*, these flanges being at right angles to the plate and parallel between upper and lower ears of the same. Screws or other fastening devices extend through the corner-ears *b* to hold the aforesaid hanger-section on a

35 door, and the flanges *c* of this hanger-section are perforated at intervals of their length, the perforations of one being in register with those of the other. However, the corner-ears of hanger-section B may be omitted and apertures for fastening devices provided elsewhere in the same. The shank *C* of another sheet-metal section of the hanger opposes the

40 section aforesaid between the flanges *c* of same and is provided with a pair of integral outer right-angle flanges *d*, that are shown for the most part parallel to each other and those of the other section, their upper ends being divergent to stiffen the wider upper portion of said

shank. The flanges *d* are perforated similar to the ones *c*, and bolts *D* extend through registering perforations in all the flanges to hold the sections of the hanger in their adjustment one upon the other, keys *e* or other suitable means being employed to prevent automatic displacement of the bolts. 55

The upper portion of the hanger-section having the flanged shank *C* is recurved to form a housing *E*, in which a track-roller *F* 60 is shown mounted, and the housing is braced by cross-bolts *G*, held against automatic displacement by nuts *f* or other suitable means. The roller is shown as provided with journals *g*, engaging bearing-apertures in plates *H*, 65 arranged in housing *E* and spaced apart by sleeves *I* on the bolts *F*, that extend through these plates and adjacent walls of said housing.

The hanger-sections are made from sheet-metal blanks operated upon by suitable dies, and to adjust said sections one upon the other the bolts *D* are withdrawn, the adjustment effected, and said bolts replaced in registering perforations of the flanges aforesaid, 70 all of which can be readily done when a hanger is in use without removal of either of its sections from working position.

Having thus described my invention, what I claim as new, and desire to secure by Letters 80 Patent, is—

A sliding-door hanger comprising two sheet-metal sections adjustable longitudinally one upon the other and each provided with integral outer vertical flanges perforated at intervals of their length, the flanges of one section being movable along those of the other section, bolts engaging registering perforations in all the flanges, means for preventing automatic displacement of the bolts, and a 85 track-roller carried by one of the sections aforesaid. 90

In testimony that I claim the foregoing I have hereunto set my hand, at Milwaukee, in the county of Milwaukee and State of Wisconsin, in the presence of two witnesses. 95

PETER H. LUITINK.
